UNITED STATES PATENT OFFICE.

WILLIAM L. KAYLOR, OF ALLEGHENY, PENNSYLVANIA.

BEARING.

No. 829,218.

Specification of Letters Patent.

Patented Aug. 21, 1906.

Application filed May 7, 1906. Serial No. 315,649.

To all whom it may concern:

Be it known that I, WILLIAM L. KAYLOR, a citizen of the United States of America, residing at Allegheny, in the county of Allegheny and State of Pennsylvania, have invented certain new and useful Improvements in Bearings, of which the following is a specification, reference being had therein to the accompanying drawings.

10 This invention relates to bearings, and more particularly to pillow-blocks and means for adjusting the same, the primary object being to provide simple and effective means for adjusting the pillow-block without disturbing the brasses or like packing of the shaft in the bearing or raising the shaft independently of the pillow-block.

15 The invention is specially adapted for mill-work, and it is designed to save time, labor, and expense by avoiding the necessity of raising the shaft and repouring a bearing when the latter becomes unduly worn by continuous use.

20 The construction of the improved bearing will be fully described hereinafter in connection with the accompanying drawings, which form part of this specification, and its features of novelty will be set forth in the appended claims.

25 30 In the drawings, Figure 1 is a view in perspective of a bearing embodying the invention. Fig. 2 is a side elevation of the same with parts thereof indicated by dotted lines. Fig. 3 is a top plan view of the base or bottom casting with the adjusting devices in position thereon, but with the pillow-block removed. Fig. 4 is a side elevation of the bottom casting, parts being indicated by dotted lines. Fig. 5 shows a side elevation 35 and end views of one of the adjusting-wedges. Fig. 6 is a section on the line 6 6 of Fig. 1 with the adjusting-wedges removed. Fig. 7 is an end elevation of the bearing, and Fig. 8 is a section on the line 8 8 of Fig. 2.

40 45 The reference-numeral 1 designates the base or bottom casting of the bearing, having an integral projection 2 on its under side adapted to be embedded in a concrete foundation to anchor the bearing securely in place. The end walls 3 extend upwardly from the base inward from the ends of the latter and are connected by side walls 4, each of which is formed with inwardly-inclined recesses 5 to accommodate driving-key 50 blocks 6, which key the pillow-block 7 against endwise movement. Side movement of the

pillow-block is prevented by the opposite side walls of the bottom casting. The upper surface of the base 1 is formed with parallel vertical partitions 8, extending from one end 60 wall of the casting to the other and, together with the side walls, forming a plurality of guideways 9 to receive flanges 10, depending from the under surface of the pillow-block and the wedge-shaped adjusting-keys 11, the 65 specific construction of which will be described hereinafter. The lower section 12 of the bearing is formed integral with the pillow-block, and the removable upper half 13 of the bearing is secured thereon removably 70 by bolts 14 and nuts 15, said bolts being inverted and applied to the lower section of the bearing through slots 16. A suitable oil-box 17 is mounted above the upper half of the bearing to supply lubricant to the shaft. The 75 under surfaces of the flanges 10 of the pillow-block are beveled, as shown in Figs. 2, 4, and 6, the base of each alternate flange being in reverse direction to adapt them to fit the oppositely-disposed wedge-shaped adjusting-keys, which are disposed alternately in opposite directions to maintain the level position of the pillow-block. The bottom of each of the guideways 9 is also inclined or beveled to correspond to the beveled surfaces of the 80 wedges.

85 Referring now particularly to Figs. 3 and 5, each of the wedges 11 is provided at its smaller end with a screw extension 18, two of which extend through openings in one of 90 the end walls of the casting, while the other two extend through similar openings in the opposite end wall, lock-nuts 19 being fitted upon the projecting ends of said screw extensions, as shown. The larger end of each of 95 the adjusting-wedges is formed with a vertically-disposed dovetail groove 20, adapted to receive a correspondingly-shaped tongue 21, formed on the extremity of an adjusting-screw 22, said screws extending through suitable openings in the end walls of the casting and being provided with square heads 23 and lock-nuts 24. The pillow-block is held by screws 25 and nuts 26, said screws entering openings 27 in the partitions 8. When it is 100 desired to adjust the pillow-block, the nuts 26 and keys 6 are first loosened, and then by manipulating the screws 22 the wedges are adjusted longitudinally to raise the pillow-block to the position required to compensate 105 for wear upon the shaft-bearing. It will be apparent that by means of the improved

mechanism described the pillow-block may be adjusted and maintained in a level position, and hence that the repouring of the bearing-packing when worn is obviated.

5 I reserve the right to make all such minor changes or modifications as may fall within the purview of the following claims.

What I claim, and desire to secure by Letters Patent, is—

- 10 1. A shaft-bearing comprising a base having a plurality of vertical partitions providing guideways thereon, the bottoms of which are inclined; a pillow-block having depending flanges beveled on their under surfaces, oppositely-disposed adjusting-wedges in said guideways below the pillow-block, and means for adjusting said wedges longitudinally.
- 15 2. In a shaft-bearing, the combination with a base-casting, having a plurality of parallel vertical partitions dividing the base into guideways having inclined bottom surfaces, said surfaces being inclined alternately in opposite directions, the end walls of said base-casting being formed with openings, of a plurality of adjusting-wedges within said guideways alternately disposed in opposite directions, and formed with screw extensions projecting through the openings in the end walls of the base, and a pillow-block having alternate oppositely-inclined depending flanges.
- 20 3. The combination with a base-casting having parallel guideways inclined alter-
- 25 nately in opposite directions, the end walls of said casting being provided with openings, of oppositely-disposed adjusting-wedges within said guideways, formed with screw extensions at one end and with dovetail grooves at the opposite end, adjusting-screws formed with tongues to engage said dovetail grooves, and a pillow-block having depending flanges projecting into said guideways above the adjusting-wedges and having their under surfaces inclined to correspond to the bevel of said wedges.
- 30 4. In a shaft-bearing, the combination with a base-casting having parallel guideways, the bottoms of which are beveled alternately in opposite directions, of adjusting-wedges within said guideways arranged alternately in opposite directions and having screw extensions and dovetail grooves, lock-nuts arranged on said screw extensions, adjusting-screws extending through the end walls of the casting and formed with tongues fitting the grooves of the adjusting-wedges, and a pillow-block having depending flanges, the under surfaces of which are alternately beveled in opposite directions to adapt them to the inclined surfaces of said wedges.

35 In testimony whereof I affix my signature in the presence of two witnesses.

WILLIAM L. KAYLOR.
